Primary Examiner — Robert M Spear*Assistant Examiner* — Kendra L Hamilton(74) *Attorney, Agent, or Firm* — James C. Eaves, Jr.;
 Bingham Greenebaum Doll LLP(57) **CLAIM**

The ornamental design of a horseshoe with clips, as shown and described.

DESCRIPTION

FIG. 1 is a bottom-front perspective view of a horseshoe with clips, showing my new design;

FIG. 2 is a top-rear perspective view thereof;

FIG. 3 is a rear elevational view thereof;

FIG. 4 is a front elevational view thereof;

FIG. 5 is a top plan view thereof;

FIG. 6 is a bottom plan view thereof; and,

FIG. 7 is a right elevational view, the left side elevational view being a mirror image thereof.

In the drawings, the broken lines depict environmental subject matter only and form no part of the claimed design.
